UNITED STATES PATENT OFFICE.

HORACE G. KENNEDY, OF DENVER, COLORADO, ASSIGNOR OF ONE-HALF TO JOHN A. HINGLEY, OF DENVER, COLORADO.

GRINDING ATTACHMENT.

Application filed September 18, 1919. Serial No. 324,437.

To all whom it may concern:

Be it known that I, HORACE G. KENNEDY, a citizen of the United States, residing at Denver, in the county of Denver and State of Colorado, have invented certain new and useful Improvements in Grinding Attachments; and I do hereby declare the following to be a full, clear, and exact description of the invention, such as will enable others skilled in the art to which it appertains to make and use the same.

This invention relates to grinders and while particularly adapted to internal grinders and especially to internal grinder attachments to a machine having a spindle and having work with a relatively longitudinal movement to said spindle and especially to an internal grinder attachment for a lathe, is not limited thereto.

An object of this invention is to provide a grinder for auto cylinders and the like that may be quickly and readily adjusted to suit the varying diameters of the cylinders being ground that may be rotated on a spindle of a lathe or similar machine.

A further object of this invention is the provision of a compact, simple, and inexpensive eccentrically variable grinder attachment for a lathe and the like.

A further object of this invention is to provide an internal grinder which may be attached to the spindle of a lathe or similar machine in which a cylinder is held concentric with the spindle and in which it might, in cases, be desired to provide such a grinder in a compact form so that the same can be easily transported and can be inserted into relatively small cylinders and one that can be readily and quickly adjusted while the spindle is rotated.

With the above and other objects in view, the invention consists in the novel features of construction, the combination and arrangement of parts hereinafter more fully set forth, pointed out in the claims and shown in the accompanying drawings, in which

Figure 1 is a central sectional elevation of my grinder, showing a spindle to which it is attached broken away and also a cylinder being ground; partly broken away,

Figure 2 is a transverse section taken on the line 2—2 of Figure 1,

Figure 3 is a side elevation, showing a

cylinder in section taken at approximately the position shown in Figure 1. 55

Figure 4 is a transverse section on the line 4—4 in Figure 3, looking in the direction of the arrows and the grinder being omitted,

Fig. 5 is a transverse section taken at 5—5 of Fig. 3, looking in the direction of the 60 arrow,

Figure 6 is a detailed sectional view taken on the line 6—6 of Figure 1, and

Figure 7 is an elevation of a detail of the counter shaft and mount therefor. 65

In carrying out my invention, the same comprises a spindle 1, said spindle being most generally a spindle of a lathe, although it might be of a milling machine or other shop machine, such as is commonly found in shops, or a special machine spindle. A nut 2 is provided with threads co-mating with the threads of spindle 1 and said nut is also extended to form an extension of spindle 1 and flanged as at 2^a. Threaded upon said extension is a member 3 which is flanged at 3^a, and between the flanges 2^a and 3^a are ball bearings 4 and 4'. The member 3 serves to form an inner mount for the ball bearings and the flanges hold the ball bearings in fixed relation. The pulleys 4^a and 4^b constitute a unitary structure freely rotating on the ball bearings at a higher speed than the spindle 1. 75

The member 3 is extended into an arm 3^c in a direction lateral to its axis and on this arm is pivoted at 13 a lever 12. Straddling the lever 12 are the pulleys 5^b and 10^b mounted upon a counter shaft 11, said counter shaft being suitably arranged within a bearing at 90 the lower end of the lever 12. These pulleys 5^b and 10^b are both affixed to shaft 11 so that when one is rotated, the other likewise rotates. 80

A belt passes from pulley 4^b to 10^b so that when the pulley 4^b is rotated by main drive rotating pulley 4^a, pulley 10^b is rotated, which in turn will rotate 5^b. The belt passes from pulley 5^b to pulley 5 so that when pulley 5^b is rotated, the pulley 5 is also rotated and like rotates a spindle 6. Mounted upon the outer end of spindle 6 is a grinder 6^a. A spring 14 is attached to the arm 3^c and also to lever 12 for the purpose of keeping taut the belts between said pulleys. 100

The spindle 6 is arranged within a suit-

able housing 25, said housing being pivotally connected with the member 3 by means of the arms 24 which are pivotally connected as at 16 to one side of the member 3. 5 The concentric relation between the spindle 6 and the spindle 1 is maintained by means of spring 23, which is affixed to the member 3 by means of a bearing 23^a, the ends of said spring being engaged beneath the pins 10 23^b carried by the housing 25 and in order to produce eccentricity between the spindle 1 and the spindle 6 and overcome the pulling of spring 23, suitable wedges 18 are disposed between the inclined portions 3^c of member 15 3 and the outer ends of arms 24^a which are disposed upon opposite sides of the housing 25 from the arms 24, thus causing an angular movement of the spindle 6 about the pivot 16, pivot 16 being eccentric relative to 20 spindle 1. The wedges 18 are connected by means of a rod 19, one end of which is screw-threaded and passes through the bearings 3^a and through the correspondingly threaded bore of a ratchet 20. The connecting rod 19 being fixed from angular movement relative to its axis and ratchet 20 being free to rotate, it will be apparent that upon rotation of the ratchet 20, the wedges 25 18 will be drawn toward the operating pulleys so that spindle 6 will be lowered in an eccentric relation to spindle 1 and will be held from excessive movement by means of the spring 23. Adjustment to increase the eccentricity of the grinding wheel may be 30 effected during operation of the grinder by manipulating small lever 21, which carries a pivoted pawl 22, normally pressed inward by a spring 22^a. A single downward pressure upon the outer end of lever 22 causes 35 a very small outward movement of the grinding wheel. To permit restoration of the wheel toward a position concentric with the main spindle 1 the ratchet wheel may be rotated in the reverse direction by the 40 fingers, or otherwise, after the grinder has been stopped in order to remove a finished work piece. It will be noted in Figure 1 that the spindle 6 which is arranged within the housing 25 rotates within suitable bearings 6^b arranged within the housing and disposed between the walls of the housing 45 and the spindle. 50

Assuming now that a cylinder A is mounted upon the cross-feed of an ordinary lathe 55 and en-bloc with a series of cylinders and it is desired that these cylinders may all be bored at one sitting all that is necessary is to screw nut 2 upon the spindle 1 of the lathe which has a standard screw thread nut 60 2 having a standard screw thread to co-mate with the threads on the spindle and to affix a belt from some power unit over pulley 4. The work having been correctly centered on the cross-feed relative to spindle 1, it 65 then can be moved longitudinally relative

to spindle 1 by the ordinary lathe mechanism and the spindle 6 eccentrically adjusted for increasing diameter of grinding as hereinbefore described and when the work of grinding this cylinder is completed, spring 70 23 tends to accelerate the return of spindle 6 to its normal concentric relation.

In Figure 1, it will be noted that the spindle 6 has been eccentrically set with respect to the spindle 1 so that the grinding 75 member 6^a forms contact with the cylinder A, the wedges 18 being moved outwardly toward the grinder by rotating the ratchet 20, by means of the spring 23 the spindle 6 will be returned to its concentric position, 80 relative to the spindle 1. After the first cylinder has been ground, the next cylinder can be quickly and accurately placed in proper relation by operation of the cross-feed so that the same can be quickly ground 85 by this device. While this device commends itself especially to lathe work, it is obvious that nut 2 could be adapted to operate upon the spindle of a milling machine and the same relative movements obtained or it 90 could be made to operate in any machine in which there is a provision for movement of work relative to a spindle.

In placing this device in position for operation upon the interior of a cylinder, 95 the grinder 6^a is inserted within the end of the cylinder, the spindle 6 at this time being in concentric relation with the spindle 1 and as soon as the grinder 6^a has been inserted to the proper position, the lugs 18 100 are adjusted within their guides to move the spindle 6 eccentric to the spindle 1 so that the grinder 6^a will engage with the interior surface of the cylinder A, as clearly illustrated in Figures 1 and 3. The grinding 105 operation is then carried on until the interior of the cylinder is sufficiently ground. The wedges 18 are then moved toward the grinder 6^a until the spindle 6 is again concentric with the spindle 1 so that the grinder 110 6^a can be readily removed from the interior of the cylinder without contacting with the inner walls of the cylinder.

What I claim is:

1. In mechanism for grinding internal 115 surfaces, a rotatable support having a relatively immovable extension member substantially parallel with the axis of the support adapted to enter the bore of a hollow body, a grinding tool spindle adjustably carried by said extension member substantially parallel therewith, and means whereby said spindle may be adjusted with respect to said extension member in order to vary its eccentricity with respect to the axis of said 120 extension member.

2. In grinding mechanism of the class described, a rotatable support, a grinding tool spindle carried by the support substantially parallel with the axis and rotatable inde- 125 130

pendently of said support, means for adjusting the grinding tool spindle to vary the degree of eccentricity thereof with respect to the axis of said rotatable support, said means including a device constantly exerting a yielding force tending to move the grinding wheel spindle toward said axis and a device for positively moving said spindle away from said axis in opposition to the force of said yielding device.

3. In grinding mechanism of the class described, a rotatable support, a grinding tool spindle carried by the support substantially parallel with the axis and rotatable independently of said support, and means including a wedging device for adjusting the grinding tool spindle to vary the degree of eccentricity thereof with respect to the axis of said rotatable support.

20 4. In grinding mechanism of the class described, a rotatable support, a grinding tool spindle carried thereby substantially parallel with the axis and rotatable independently of said support, means for adjusting the grinding tool spindle to vary the degree of eccentricity thereof with respect to the axis of said rotatable support, said means including a device for exerting a yielding pressure tending to lessen the degree of eccentricity and adjustable wedges for increasing the degree of eccentricity.

35 5. In grinding mechanism of the class described, a rotatable support, a lever pivoted to the support at one side of the axis thereof, a grinding tool spindle journaled in the lever on an axis substantially parallel with the axis of the rotatable support, said spindle being rotatable independently of said support, a yieldable device constantly exerting force tending to move the lever in a direction to lessen the degree of eccentricity of said axis, and adjusting means adapted to move the lever positively in a direction to increase the degree of said eccentricity.

40 6. In grinding mechanism of the class described, a rotatable support comprising an extension member substantially parallel with the axis of rotation of said support, a grinding tool spindle carried by said extension member parallel with said axis, said spindle being rotatable independently of said support, and adjustable so as to vary the degree of eccentricity of said spindle with respect to said axis, a wedge bar parallel 45 with said spindle for adjusting it and means

whereby the wedge bar may be moved longitudinally.

7. In grinding mechanism of the class described, a rotatable support comprising an extension member substantially parallel 60 with the axis of rotation of the support, levers pivoted to said extension member transversely thereof, a grinding tool spindle journaled in said levers and rotatable independently of said support, a spring tending 65 to move said levers in a direction to reduce the degree of eccentricity between said spindle and axis, and a bar having wedge surfaces engaging between said extension member and the levers adapted to move the levers 70 in opposition to the force of the spring.

8. In a grinding attachment for lathes or the like, a support adapted to be secured to the spindle of a lathe, a grinding tool spindle hinged to said support, means for rotating the spindle and support at different relative speeds, and means for changing the degree of eccentricity between the axes of 75 the support and spindle.

9. In a grinding attachment for lathes or 80 the like, a support adapted to be secured to the spindle of a lathe, a grinding tool spindle hinged to said support, means for rotating the spindle and support at different relative speeds, and means for changing the 85 degree of eccentricity between the axes of the support and spindle while the grinding tool is in operation.

10. A cylinder grinding attachment for lathes and the like including a support 90 adapted to be secured to the spindle of the lathe, a grinding tool spindle adjustably mounted on the support, means for rotating the support and spindle at different relative speeds, and means for changing the degree 95 of eccentricity between the axes of the support and spindle.

11. A cylinder grinding attachment for lathes and the like including a support adapted to be secured to the spindle of the 100 lathe, a grinding tool spindle adjustably mounted on the support, means for rotating the support and spindle at different relative speeds, and means for changing the degree of eccentricity between the axes of the support and spindle while the grinding tool is 105 in operation.

In testimony whereof I affix my signature.

HORACE G. KENNEDY.
